HOT-AIR FURNACE AND VENTILATING SYSTEM.

Application filed November 26, 1926. Serial No. 150,672.

This invention relates to a hot air furnace and ventilating system.

The chief object of the invention is to equip a hot air furnace with means and controls 5 therefor, whereby the same will supply relatively pure air to the rooms to be heated.

The chief feature of the invention consists in providing a by-pass control arrangement between the cold air return and smoke pipe or 10 chimney, and arranging the same so that a portion of the returned air is by-passed to the smoke pipe and a similar amount is supplied from without the building heated.

Another feature of the invention consists 15 in by-passing a portion of the impure returned air through the fire for draft and closing the previously indicated by-pass so that the draft will not be impaired or in by-passing a portion each way if desired.

20 The full nature of the invention will be understood from the accompanying drawings and the following description and claims:

In the drawings Fig. 1 illustrates a heating system for a building, the furnace being partly 25 shown in elevation and partly in section, and the several conduits being similarly illustrated. Fig. 2 is an enlarged central sectional view of a portion of the fire bowl.

In the drawings 10 indicates a casing of 30 a furnace having a header or top 11 from which extend the usual hot air pipes 12 that discharge into the outlets 13 usually provided with registers 14. The building is also provided with a cold air register or intake 15, 35 which is connected by the cold air duct or return pipe 16 to said casing 10 near the bottom thereof and a boot or settling chamber 17 to which reference will be had later. The intake 18 which connects the cold air register opening 40 with at least one return pipe 16, has another opening 19 and a cold air register or control 20 is associated therewith for supplying fresh air from without the building to the return pipe 16. The furnace is also provided 45 with a smoke pipe 21 having the usual check damper 22 controlled by chain 23 which is also connected to the draft damper 24 carried by the ash pit door 25. The furnace has the usual fire door 26. The heating head 27 discharging through radiator 127 by way of con-

duit 28 to the smoke pipe 21, and the fire bowl 29, flame shell 30, grate 31 and the bowl casing 32 complete the fire chamber. The ash pit 33 includes an intermediate member 34 which supports the fire bowl and chamber 55 arrangement above the ash pit and the same includes an annular channel 35 with a plurality of ports 36 that discharge inwardly beneath and below the level of the grate. A conduit 37 extends from said member 34 and 60 beyond the furnace casing 10. The casing 32 includes a plurality of vertical passages 132 which communicate at their lower ends with channel 35 by ports 135 and at their upper ends with an annular channel 133 in said 65 casing. Said channel 133 discharges air inwardly above the fire brick or bowl 29 through ports 136, see Fig. 2.

The boot 17 includes a depending baffle or partition 38 and an adjacent outlet 39 connected by a by-pass 40 to the smoke pipe and the cross sectional area of this by-pass is at least equal to that of the fresh air intake 20. The capacity of boot 17 is at least equal to and preferably greater than that of the pipe or 75 pipes entering or leaving the same respectively so that the air therein has a decreased velocity and the baffle 38 therein tends to separate the air into hot and cold layers or components. The opening 39 is so positioned with 80 respect to baffle 38 in the boot that the air bypassed through conduit 40 is the warmer return air. When intake 20 is employed substantially none of this pure air is thus bypassed.

The branch 37 of conduit 40 and the connection of the conduit 40 to the smoke pipe 21 are differentially controlled by a dual control valve 42 operable by arm 41 and chain 43. Said chain may be associated with the pulley 44. Chain 43 may also be suitably connected with chain 23 so that the check damper 22 will be opened when by-pass 40 is open and when the draft damper 24 is opened by-pass 37 also will be opened, thereby insuring that the 90 air always will be purified by reason of the removal of a portion of the air from the boot 17 and opening 39 and replacement through the intake 20. The air in conduit 37 passes through the grate 31 from ports 36, thereby 95 100

assisting the draft. Also a part of the air is discharged into the flames above the fire pot thereby securing complete combustion when the fire is under increased draft. When the fire is to be checked, draft damper 24 is closed and the draft by-pass 37 is cut off by valve 42. If the valves are connected as indicated, and the damper 22 is opened the smoke pipe receives part of its draft from conduit 40 and the cold air return as aforesaid. It is desirable at times not to connect chain 23 with chain 43 for simultaneous operation and in that event the chain 43 is operated independently and the valve 42 is then the full equivalent of what is normally called the intermediate check damper.

When it is desired to operate the dual valve 42 independently of chain 23, it may be assumed that draft and check dampers 24 and 22 respectively, are closed, that is, the furnace is in neutral control. Elevation of chain 43 then closes by-pass 40 and opens by-pass 37 to the boot 17. Thus, substantially all the draft for the furnace is taken through opening 39. Lowering or reverse movement of chain 43 closes by-pass 37 and opens by-pass 40 and practically the entire pull of the chimney is then drawing off the heated and therefore less pure air from boot 17 through opening 39. In either event the less pure return air is being continually disposed of either through the fire as draft, or out through the smoke pipe. Fresh air, therefore, supplied through inlet 20 is being constantly introduced to the heating system in a like amount and this air passes into chamber 45 for subsequent heating.

While the invention is herein illustrated as applied to a pipe type of furnace, it will be readily understood that the same also can be readily adapted to a pipeless type of furnace, the piping being suitably modified for such purpose, and likewise while the hot air furnace is shown as of the coal or wood type, it can be of any type for heating the air, and in certain instances it may be of a simpler type wherein a part of the returned air is not passed for assisting in the draft or increasing the heating effect.

The furnace herein illustrated is also shown provided with a chamber 45 beneath the ash pit and with which the entire air heating chamber of the furnace is in direct communication. Thus, the colder air received through the intake 20 passes beneath the furnace and abstracts the heat from the ash pit before passing upwardly and around the fire bowl and over the flame shell into the several heating conduits.

The invention claimed is:

1. The combination with a hot air furnace having an air heating chamber and a smoke pipe; of an air return communicating with the ash pit and the air heating chamber of said furnace, a by-pass between said return

and said smoke pipe, a second by-pass establishing communication between the first by-pass and the fire pot of said furnace, and valve means controlling said by-passes.

2. The combination with a hot air furnace having an air heating chamber and a smoke pipe; of an air return communicating with the ash pit and the air heating chamber of said furnace, a by-pass communicating at one end with the upper part of said air return near its juncture with said ash pit and with said smoke pipe at its other end, a second by-pass communicating at one end with said first by-pass and at its other end with the fire pot of said furnace, and a single valve selectively controlling the smoke pipe and fire pot communication with the first by-pass.

3. The combination with a hot air furnace having a smoke pipe and an air heating chamber; of a horizontally disposed boot at the base of said furnace and communicating with the heating chamber and the ash pit thereof, a baffle in said boot closing the upper part of said boot at its inner end, a return pipe communicating with the outer end of said boot, a by-pass establishing communication between the upper portion of said boot and said smoke pipe, a second by-pass establishing communication between said first by-pass and the fire pot of said furnace, and valve means controlling said by-passes.

4. In a heating system the combination of a furnace having a check damper, a draft damper, means connecting the same for simultaneous operation, a smoke pipe and a fire pot, an air return connected to the furnace for recirculation, a branched conduit connected at one end to the return and at its other end to the smoke pipe and to the fire pot, valve means simultaneously and selectively controlling the communication of said conduit with the smoke pipe and fire pot, and a connection between said valve means and said draft and check damper connection for simultaneous predetermined operation of the same.

5. In a hot air furnace the combination of an air heating chamber and an ash pit, a horizontally disposed boot, a bypass therefrom having communication with the ash pit, and a baffle interposed between the boot and the heating chamber communication and arranged so that the foul air trapped by the baffle is bypassed to the pit.

6. In a hot air furnace the combination of an air heating chamber, an ash pit, a smoke pipe, a horizontally disposed boot, a bypass therefrom having communication with the ash pit, a baffle interposed between the boot and the heating chamber communication, and arranged so that the foul air trapped by the baffle is bypassed to the pit, a second bypass connected to the first bypass and connected to the smoke pipe, and valve means proportionately controlling the division of air

through the bypass directly to the smoke pipe or indirectly thereto through the ash pit.

7. A hot air heating system including in combination a cold air return register for receiving air from the building to be heated, a hot air furnace having a smoke pipe, an air heating chamber, a horizontally disposed boot at the base of said furnace and communicating with the heating chamber directly and the 10 ash pit thereof indirectly, a baffle in said boot closing the upper part of said boot at its inner end, a return pipe communicating at one end with the outer end of the boot, and at its opposite end with the register, a by-pass establishing 15 communication between the upper portion of said boot and said smoke pipe, a second by-pass establishing communication between said first by-pass and the fire pot of said furnace, valve means controlling said 20 by-passes, and a cold and fresh air intake communicating with said return pipe adjacent the cold air register.

In witness whereof, I have hereunto affixed
my signature.
